UNITED STATES PATENT OFFICE

GEOORG EMANUEL KARLSON, OF STOCKHOLM, SWEDEN

SHOE, BOOT, AND THE LIKE

Application filed February 7, 1930, Serial No. 426,634, and in Sweden January 3, 1929.

It is before known to stiffen the shank of shoes, boots or the like by means of a plate, so called shank-spring which is placed between the soles and covered by a complementary sole. Further it has been proposed to shape the shank-spring in a special manner, so that it serves as a support for the transverse arch of the foot. Also in this case a complementary sole must be used. The proposal of a shank-spring constituting a support for the transverse arch of the foot or not, and of a complementary sole separated from one another complicates the manufacturing of the shoe and, besides, shank-springs provided with a support for the transverse arch of the foot effected by forcing the material upwards tends to break through the sole and in addition hereto renders difficult the half-soling operation.

The present invention relates to an interlining, which mounted between the soles at the shank of a shoe or boot firstly constitutes a substitution for the shank-spring as well as for the complementary sole and secondly serves in an advantageous manner as a support for the transverse arch of the foot. The present interlining consists of a comparatively stiff but however springy plate, preferably of metal, which is completely or nearly so enclosed by an elastic cover or india rubber or equivalent material, which at the one end of the said plate is so shaped that it constitutes a dome shaped swell, serving as a support for the transverse arch of the foot.

The cover enclosing the said member replaces the usual complementary sole and, besides, constitutes a protection, which prevents the member from being attacked by rust. Further, the elastic cover prevents the ends of the plate from having a tearing or breaking action on the soles. Owing to the fact that the cupola-like swell is made integral with the cover it remains in a reliable manner in its position relatively to the plate, which is especially important regarding supports for the transverse arch of the foot.

A form of execution of the invention is shown in the accompanying drawings in which Fig. 1 is a longitudinal section of the present interlining. Fig. 2 is a plan view of

the interlining and Fig. 3 is a cross section of the same. Fig. 4 shows in a side view partially in section a shoe provided with the interlining.

1 is a comparatively rigid but however springy plate preferably of metal. The shape and the size of the said plate are adapted to the shank of the shoe, in which it is to be used. The plate 1 is surrounded by a cover 2 of an elastic material such as india rubber, which, preferably, encloses the plate completely. The said cover may be effected in such manner, that plates of india rubber especially prepared by the vulcanizing process and of suitable dimensions are placed at opposite sides of the springy plate and forced against each other in a suitable mould, which is heated to the necessary vulcanizing temperature, so that the plate is completely embedded. Openings 4 are provided in the metal plate and the plates of india rubber which permit the centering of the metal plate with relation to the plates of india rubber by means of guide pins. Preferably, protecting pieces 3 of a fabric or the like are placed around the ends of the plate 1. The contour of the plate, Fig. 2, corresponds substantially to the contour of an ordinary complementary sole. A dome shaped swell 5 of the cover is located above the fore end of plate 1, which is so adapted, that, as the plate has been mounted between the soles of a shoe, or boot, the rise of the insole thus effected by the said swell serves as an effective support for the transverse arch of the foot. Fig. 4 illustrates clearly the manner in which the plate is mounted between the outersole 6 and the insole 7.

The dome shaped swell 5 may be effected by providing between one of the plates of india rubber and the plate 1 one or more pieces of india rubber or the like of the intended shape. The plates of india rubber may be prepared in any suitable manner and, if necessary, provided with reinforcements for instance of a fabric.

In addition to the fact that the present interlining in an advantageous manner substitutes the ordinary shank-spring and the complementary sole, it also constitutes by 100

means of the insole an effective support for the transverse arch of the foot, which support compared with the loosely mounted instep-arch support involves the advantage of the bones being supported in the desired manner also after the shoe has been used for some time, which not always is the case when loosely mounted instep arch supports are used. Besides, it is not necessary generally to select or adapt the interlining for each wearer separately, but a certain type may be used for a certain size of shoes provided that the foot has no serious abnormalities or defects regarding its shape, a certain standardizing being thereby rendered possible.

15 I claim:

16 A shoe, boot or the like provided with a shank piece placed between the soles, said shank piece comprising a stiff but resilient plate, an elastic protective cover completely surrounding said plate, and a dome-shaped swell on said cover, stiffened by and in the vicinity of the foremost end of the plate, the shank piece serving as a support for the 20 longitudinal and transverse arches of the foot.

25 In testimony whereof I have hereunto affixed my signature.

GEORG EMANUEL KARLSON.
